ALUMINUM CUTTER

George F. Brow and Frank Rioux, East Braintree,
Mass.

Application February 10, 1943, Serial No. 475,416

3 Claims. (Cl. 30—140)

This invention relates to new and useful improvements in metal cutters and more particularly to a device for cutting aluminum.

Heretofore, aluminum could never be cut cleanly. The usual operation was to melt aluminum and blow the melted aluminum with an oxyacetylene torch, which generally left a half inch or more wide opening with extremely jagged edges.

The principal object of the present invention is to provide an implement whereby the metal can be heated to a soft state and draw a knife through this particular area to perform the cutting operation.

Other objects and advantages of the invention will become apparent to the reader of the following description.

In the drawing:

Figure 1 represents a side elevational view of the device.

Figure 2 is a vertical sectional view through the head structure.

Figure 3 is a bottom plan view of the head structure with the tips removed.

Figure 4 is a front elevational view of the cutter.

Figure 5 is a side elevational view of the cutter with the blade removed.

Figure 6 is a front elevational view of the structure shown in Figure 5.

Figure 7 is a perspective view of the cutter blade.

Referring to the drawing wherein like numerals designate like parts, it can be seen in Figure 1, that numeral 5 denotes a union to which gas lines 6, 7 are connected and from which extends a tube 8. Valves 9, 10 are provided in the usual way for controlling the supply of gas to the mixing union 6.

The tube 8 has a laterally disposed end portion 11 terminating in a socket 12 for the reception of a threaded nipple 13 located on a head or box 14 into which mixed gases pass.

Numerals 15, 16 denote a pair of flame tips, the tip 15 being slightly longer than the tip 16 and being the greatest removed from a cutter unit generally referred to by numeral 17.

The tips 15, 16 have threaded portions 18 disposed into the box 14.

The box 14 has an extension at one end formed with a vertically disposed opening 19 into which is disposed a bar 20 forming part of the unit 17.

This bar is held to the block 14 by a set screw 21. The lower end of the bar 20 has an offset plate 22, defining a shoulder 23 against which can abut the upper end of an inverted L-shaped blade 24, the upper portion of which is formed with openings 25, 26 to receive a stud bolt 27 and a retaining pin 28 on the offset plate 22.

A nut 29 is provided on the stud bolt 27 to secure the blade in place against the offset plate 22. Numeral 30 denotes the cutting edge of the blade 24 which is opposed to the location of the tips 15, 16.

It can now be seen, that when the tips 15, 16 have been lighted and the cutter bar 20 properly adjusted, a sheet of aluminum can be heated to a soft state and by exerting a pull on the tube 8, the blade 30 can be drawn through the softened area of the metal, leaving a straight and clean cut.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A metal cutting device comprising a supply tube for inflammable gas, a head structure at one end of the tube, a cutter unit including a cutting edge and a burner tip projecting from the head and adjacent the cutter unit.

2. A metal cutting device comprising a supply tube for inflammable gas, a head structure at one end of the tube, a cutter unit including a cutting edge and a burner tip projecting from the head and adjacent the cutter unit, and a second burner tip at the opposite side of the first-mentioned tip from the cutter unit and being somewhat longer than the first-mentioned burner tip.

3. A metal cutting device comprising a supply tube for inflammable gas, a head structure at one end of the tube, a cutter unit including a cutting edge and a burner tip projecting from the head and adjacent the cutter unit, said cutter unit comprising an adjustable bar and a removable blade on the bar having said cutting edge.
